UNITED STATES PATENT OFFICE

PHILLIP N. MURAKAMI, OF WAIKANE, TERRITORY OF HAWAII

ELECTRIC SADIRON

Application filed February 23, 1932. Serial No. 594,689.

This invention appertains to new and useful improvements in sadirons, and more particularly to a novel sadiron of the electrical type.

5 The principal object of this invention is to provide a sadiron which is water-insulated to prevent burning of work.

Other important objects and advantages of the invention will become apparent to the 10 reader of the following specification.

In the drawings:—

Figure 1 represents a sectional view through the iron.

Fig. 2 represents a top plan view of the 15 iron showing the jacket and cover plate for the element removed.

Fig. 3 represents a top plan view, partly in section showing the shoe plate.

Fig. 4 represents a transverse sectional 20 view through the shoe plate.

Fig. 5 represents a fragmentary detailed sectional view taken substantially on line 5—5 of Fig. 3.

Fig. 6 represents a fragmentary detailed 25 sectional view through the heating element assembly.

Fig. 7 represents a rear end elevational view of the iron.

Fig. 8 represents a sectional view taken 30 substantially on line 8—8 of Fig. 1.

Referring to the drawings wherein like numerals designate like parts, it can be seen that numeral 5 represents the shoe plate which is of the usual iron conformation and 35 this is provided with a shoulder 6 around its perimeter upon which is supported the jacket 7 which forms a hood for the heating element assembly generally referred to by numeral 8.

40 Numeral 9 represents a raised wall upon the plate 5 having the same configuration as the perimeter of the plate 5 and this is connected at several points by the bridge pieces 10, each of which is provided with 45 one or more openings 11 which establishes

communication between the compartments 12, 13, 14 and 15, water being supplied to these compartments by the tube 16 at the butt end of the shoe plate 5, which merges at its outer end in a funnel-like structure 17 50 having a needle valve closure 18 thereon.

This heating element assembly 8 is interposed between the bridges 10 and the cover plate 19, the cover plate 19 being provided with depending flanges 20 which engage in 55 overlapping relation, the wall 9.

The jacket 7 is secured to the plate 5 by tie bolts 21 which extend downwardly from the brackets 22—22, through the jacket 7 and cover plate 9, as well as through the 60 assembly 8 to thread into the plate 5. A jamb nut 23 is provided on each of these tie bolts 21 for engagement against the top side of the cover plate 19 and the spacers 24 are provided on the tie bolts 21 between 65 the assembly 8 and the plate 5, as in the manner substantially shown in Fig. 1.

Numeral 25 represents a bore extending transversely into the plate 5 from the side thereof and in this is disposed the barrel 26, 70 the bore therethru opening at its inner end through the side thereof, as at 27. This barrel 26 is provided with a threaded extension 28 which threads into a counter-threaded bore in the plate 5. The barrels 26 can be 75 rotated, so that its open end 27 can register with the ducts 29 in the plate 5. This affords a drain for the water compartments 12 to 15 inclusive.

The rear wall of the jacket 7 is provided 80 with an opening from the upper portion of which extends an inclined flange 30 against which the electric plug 31 serves and is tensionally urged by the leaf spring 32. The plug 31 is provided with internal contacts 85 with which the prongs 33 on the plate 19 are engageable, and the plug 31 is provided with notches 34 therein which receive the offset 35 of the spring 32 whereby the plug 31 is 90 retained against accidental displacement.

Interposed between the upper end of the brackets 22—22 is the handle 36. The heating element assembly 8 includes a pair of zig-zaggedly arranged elements 37 (see Fig. 5 2) of one continuous wire, which is connected at its ends to the prongs 33. Located upon and below the element 37 are mica sheets 38.

While the foregoing specification sets 10 forth the invention in specific terms, it is to be understood that specific changes in the shape, size and materials may be resorted to without departing from the spirit and scope of the invention as claimed hereinafter.

15 Having thus described my invention, what I claim as new is:—

A sadiron of the character described comprising a shoe plate, a jacket for disposition upon the plate, a basin in the plate for receiving water, an inlet to the basin, a closure for the basin, means for securing the jacket to the plate, the rear end of the said jacket provided with an opening, a plug, a pressure plate extending outwardly from the 20 jacket adjacent the opening and against which the plug can bear, contact prongs on the closure for engagement by the plug, and spring means on the jacket for engagement against the plug to clamp the same against 25 the said pressure plate.

In testimony whereof I affix my signature.

PHILLIP N. MURAKAMI.
